UNITED STATES PATENT OFFICE

HORACE E. SMYTHE, OF PITTSBURGH, PENNSYLVANIA, ASSIGNOR, BY MESNE ASSIGNMENTS, TO OPEN HEARTH COMBUSTION COMPANY, A CORPORATION OF NEW JERSEY

FURNACE

Application filed January 9, 1922. Serial No. 527,985.

My invention relates to open hearth melting furnaces of the regenerative type.

In the usual construction of such furnaces, the two gas regenerators are placed at the ends of the furnace, and the two air regenerators are placed between the gas regenerators and opposite each other. In the present invention the positions of the air and gas regenerators are reversed from those in the said usual construction of furnaces. By this reversal the furnace does not have the undesirable slope, slopes, or outlets for conducting the air over the top of the gas passages. My invention avoids the objectionable practice of keeping the air and gas separated until they enter the port or ports opening directly into the melting chamber. By my invention the gas is conveyed up through straight vertical passages directly in front of, and in the line of the travel of, one or more air passages which also come up through straight vertical passages at the very ends of the furnace, so that the air and gas are thoroughly mixed prior to their entrance into the melting chamber, the gas traveling from said vertical passages without hoods or ports and preferably in open troughs to be explained fully hereinafter. Other objects of this invention will be better understood after the latter has been described.

Referring to the accompanying drawings, Fig. 1 is a vertical section taken centrally and longitudinally through the melting chamber; Fig. 2, a horizontal section taken on the line II—II of Fig. 1; Fig. 3, a horizontal section taken on the line III—III of Fig. 1, the upper portion of the figure being a plan view and parts being broken off and the section on the left side being moved toward the right and the gas-valve being omitted; Fig. 4, a vertical section on the line IV—IV of Figs. 1 and 3; Fig. 5, a vertical section on the line V—V of Fig. 1, the section being continued only slightly into the air regenerator; Fig. 6, a vertical section on the line VI—VI of Fig. 1; Fig. 7, a vertical section on the line VII—VII of Fig. 3; Fig. 8, a vertical section on the line VIII—VIII of Fig. 3; Fig. 9, a vertical

section on the line IX—IX of Fig. 3, with the gas-valve added; Fig. 10, a central vertical section through one end of a furnace having a modification of my invention; Fig. 11, a horizontal section through one end of a furnace showing a second modification of my invention; and Fig. 12, a vertical section through one end of a furnace showing a third modification of my furnace.

Referring first to Figs. 1 to 9, 1 designates the furnace chamber or melting hearth of a regenerative furnace. As the right and left portions of the structure about to be described are duplicates, I will designate the left-hand parts by numerals and the corresponding right-hand parts by the same numeral followed by a letter. Except when deemed necessary or desirable the left side only of the furnace and its accessories will be described, it being understood that the two sides are transposed like the parts of a pair of gloves.

2 is a central air-flue extending up vertically from the air passage 3 to the chamber 4, and 5 is a central vertical gas-flue extending up from the gas-passage 6 to the chamber 4 directly in front of the flue 2. 7 and 8 are two auxiliary vertical air-flues, one being in front and the other at the rear of the air-flue 2. They extend down to the air-passage 3 and up to the chamber 4. The gas flue 5 is between the air-flue 2 and the furnace chamber 1, and the gas-passage 6 is between the air-passage 3 and the center line of the furnace structure, that is, the air-flues and passage are at the very end of the furnace structure and the gas-flue and passage are nearer the center thereof. The roof 9 of the chamber 4 is inclined downwardly toward the chamber 1 and the lateral walls 10 thereof converge toward the said chamber, the roof 9, the walls 10, and the floor 11 of the gas-trough 12 forming a contracted throat or inlet 13 to the melting chamber. At the sides of the trough-floor 11 are the converging trough-sides or lateral walls 14 which preferably extend from the top of the air-flue 2 to the throat 13, there being a low bridge-wall 15 between the sides 14 and also between the flues 2 and 5. The

60

65

70

75

80

85

90

95

100

trough-sides extend only partially up in the chamber 4, forming lateral air-courses 16 between each trough-side and its adjacent side-wall 10. The roof 9 is extended sufficiently toward the center of the furnace to direct fluid from the chamber 4 down toward the bottom or floor of the chamber 1.

8 The air passage 3 is connected to the air-regenerator 17 by the flue 18 and the gas-passage 6 is connected to the gas-regenerator 19 by the flue 20. The checkerwork has not been shown in the regenerators as it is well known.

10 The regenerator 17 is connected by the passage 21 to the valve box 22 and the regenerator 19 is connected by the passage 23 to the port 24. The ports 25, 26, and 26^a of the sliding valve 27, when slid to its right-hand limit, as shown on Fig. 9, register respectively with the ports 24, 32, and 24^a, the port 32 communicating below with the stack flue 33. When the valve is slid to its left-hand limit the ports 26, 26^a, and 25^a 20 of the valve register respectively with the ports 24, 32 and 24^a, the ports 26 and 26^a being connected by the passage 34 in the valve. The valve has the end passage 28 leading from the port 25 to the gas-inlet 25 port 29 at the top of the valve. The ports 29 and 29^a alternately register with the gas-inlet port 30 in the fixed plate 31 covering the ports 29 and 29^a and water-sealed in connection therewith.

30 35 The passage 21 has the port or valve-seat 35 opening into the valve-box or casing 36 which opens downwardly through the port or valve-seat 37 into the stack-flue 33. The valve-seats 35 and 37 are controlled by the 40 mushroom valves 38 and 39 having their stems 40 and 41 extending up through the valve-box 36 and operated by any suitable means.

45 42 is a blower which delivers a forced blast of air to the supply-pipe 43, the latter leading to the branch pipes 45 and 45^a having the dampers or valves 44 and 44^a. The pipes 45 and 45^a lead to the valve chambers 36 and 36^a. The valves 44 and 44^a are operated by the lever 46 and are moved thereby in one direction to have the valve 44 cut off or regulate the air in the branch pipe 45, and in the opposite direction to have the valve 44^a cut off or regulate the air in the branch pipe 45^a.

50 55 The operation of the apparatus shown in Figs. 1 to 9 is as follows: Assuming that the mushroom valves are as in Figs. 7 and 8, and the sliding valve 27 is in the dotted position shown in Fig. 9, and the regenerators 17^a and 19^a are hot, and the lever 46 is swung as in Fig. 7, air from the blower 42 will be forced through the air-supply pipe 43, the branch pipe 45^a, the valve-chamber 36^a, the valve-seat 35^a, the air-passage

21^a, the air-regenerator 17^a, the air-flue 18^a, the air-passage 3^a and the air-flues 2^a, 7^a and 8^a, to the air and gas mixing chamber 4^a. At the same time gas flows from a suitable source of supply through the inlet ports 30 and 29^a, the end passage 28^a, the ports 25^a and 26^a and 24^a, the gas-passage 23^a, the gas-passage 6^a, and the gas-flue 5^a to the gas-trough c and the chamber 4^a where it having been regenerated meets the regenerated air whose course has just been traced. The mingled gas and air in the chamber 4^a having been ignited pass through the trough, the courses 16^a, and the throat 13^a into the melting chamber 1, whence the waste gases pass through the throat 13, to the chamber 4 where they divide. One portion of the waste gases flows through the air flues 2, 7, and 8, the passage 3, the flue 18, the regenerator 17, the passage 21, the valve-seat 35, the valve-casing 36 and the valve-seat 37 to the stack-flue 33. The other portion of the waste gases flows through the flue 5, the passage 6, the flue 20, the gas-regenerator 19, the passage 23, the ports 24 and 25, the valve-passage 34, and the ports 26^a and 32 to the said stack-flue 33. The waste gases reheat the regenerators 17 and 19 while the air and gases flowing to the chamber 1 are absorbing heat from the regenerators 17^a and 19^a.

55 In order to reheat the regenerators 17^a and 19^a and still regenerate the ingoing air and gas, the valve 39 is lowered to its seat 37, the valve 38 remains open, the valve 39^a is opened, the valve 38^a remains open, the valve 27 is slid to the full-line position shown on Fig. 9 and the lever 46 is swung to its dotted position. Air will flow from the blower 42 through the pipe 43, the branch pipe 45, the valve-chamber 36, the valve-seat 35, the passage 21, the hot air-regenerator 17, the flue 18, the passage 3, and the flues 2, 7, and 8 to the mixer chamber 4. The gas flows through the ports 30 and 29, the passage 23, the ports 25 and 24, the passage 23, the gas-regenerator 19, the flue 20, the passage 6, and the flue 5 to the said chamber 4. The gas and air burn preliminarily in the chamber 4 and enter the melting chamber 1, from which the waste gases travel to the passages 21^a and 23^a in the reverse direction to that which the air and fuel gas take while flowing to the furnace through the passages, flues and ports bearing the letter *a* after the reference numerals. From the passage 21^a the waste gases pass through valve-seat 35^a, the valve-chamber 36^a, and the valve-seat 37^a to the stack-flue 33. The waste gases in the passage 23^a flow through the ports 24^a and 26^a, the passage 34, and the ports 26 and 32 to the said stack-flue.

60 65 When the regenerators 17 and 19 should be again heated, the several parts are shifted to the original position and the courses

70

of the air, fuel-gas and waste gases are those first described. The valves are alternately shifted as long as the furnace is in operation, the fluids flowing therein in a manner apparent from the foregoing description.

- 5 It is seen that the gas flue 5 is directly ahead of the air flues, being separated from the air before combustion only by the side walls 14 of the tapered trough and by the 10 low bridge-wall 15. Thus the air is conveyed directly over and in close contact with the gas for a desirable distance, approximately from 3' to 6', before passing through the throat 13 and into the melting chamber 15 where the combustion, begun in the chamber 4 and particularly in the tapering trough or channel *c*, is completed. By the aid of suitable draft and induced pressure, the incoming air and gas are held in the chamber 20 4 within the confines of walls which converge to the throat 13. The mixed and burning gas and air are thus concentrated in the chamber 4 and forced therefrom at a great velocity which facilitates their mixing, and 25 consequently their combustion, the burning gas and air being impinged directly upon the bath in the chamber 1 whereby the furnace structure, particularly its lining is given longer life.
- 30 The end walls of the furnace chamber or hearth slope toward the throat 13 at an angle of approximately 135 degrees, as shown in Figs. 2 and 11. The air and gas passages entering at each end of the chamber 1 and at the adjacent portions of the chamber 1 are so related to the throat as to form approximately a Venturi section.

By locating the air-flues at the ends of the furnace and the gas flues in advance of 40 them, I may use the entire width of the furnace for the air flues, as shown in Fig. 2, where the air-flues 2, 7, and 8 extend entirely across the width of the furnace.

The mushroom valves 38 and 38^a may be 45 used to regulate the flow of fluid through their seats.

In Fig. 10, the gas flue may be blocked up or omitted or used for air, and the fuel gas is supplied through metal pipes 47 (only 50 one shown) extending to the trough or channel *c*. The fuel to be used with this type of furnace is coke-oven-gas, natural gas and gases of a similar nature. In new structures air regenerators only will be used.

55 In Fig. 11, I show the end of the furnace contracted in width so that there is but one air flue 278 having the combined width of the gas channel *c* and the courses 16, but the width of the air-flue may be varied. 60 With the flue 5 closed or not used, gas may be admitted through the pipes 47 shown in dotted lines, the same as in Fig. 10.

In Fig. 12, I show how I adapt a furnace of usual construction to my invention. In 65 the said construction the gas-passage 6' leads

directly up to the flue 2, which corresponds in position to the central air-flue 2 (Fig. 2), and the air-passage 3' leads upwardly and outwardly to air-flues corresponding to the positions of the flues 7 and 8 (Fig. 2). I 70 arrange the gas-flue in front of the air-flue 2 and connect the gas-passage 6' to the flue 5 by the inclined flue-section 6'', and I connect the air-passage to the air flue 2 and the flues 7 and 8, if present, by an inclined passage 3'', shown in dotted lines.

I claim:—

1. A furnace having a central melting chamber and at each end a preliminary combustion chamber, a pair of air and gas regenerators for each end of the furnace, the gas-regenerators being between the air-regenerators, means connecting each preliminary combustion chamber to its air-regenerator, the said means extending upwardly at the 80 extreme ends of the furnace for the full width thereof, and an open-top channel in the preliminary combustion chamber leading from the gas inlet to the melting chamber.

2. A furnace having a central melting chamber and at each end a preliminary combustion chamber, a pair of air and gas regenerators for each end of the furnace, the gas-regenerators being between the air-regenerators, means connecting each preliminary combustion chamber to its air-regenerator, the said means extending upwardly at the 90 extreme ends of the furnace for the full width thereof, and an open-top channel in the preliminary combustion chamber leading from the gas inlet to the melting chamber.

3. A furnace having a central melting chamber and at each end a preliminary combustion chamber, a pair of air and gas regenerators for each end of the furnace, the gas-regenerators being between the air regenerators, means connecting each preliminary combustion chamber to its air-regenerator, the said means extending upwardly 105 at the extreme ends of the furnace for the full width thereof, an open-top channel in the preliminary combustion chamber leading from the gas inlet to the melting chamber, and a bridge-wall across the channel back 110 of the gas-flue.

4. A furnace having a central melting chamber and at each end a preliminary combustion chamber, a pair of air and gas regenerators for each end of the furnace, the gas-regenerators being between the air-regenerators, means connecting each preliminary combustion chamber to its air-regenerator, the said means extending upwardly 120 at the extreme ends of the furnace for the full width thereof, and an open-top channel in the preliminary combustion chamber leading from the gas inlet to the melting chamber, and the sides of the channel being separated from the sides of the preliminary 125

chamber so as to form the lateral air-courses.

5. A furnace having a central melting chamber and at each end a preliminary combustion chamber, a pair of air and gas regenerators for each end of the furnace, the gas-regenerators being between the air-regenerators, means connecting each preliminary combustion chamber to its air-regenerator, the said means extending upwardly at the extreme ends of the furnace for the full width thereof, and an open-top channel in the preliminary combustion chamber leading from the gas inlet to the melting chamber, the preliminary chambers being narrowed toward the melting chamber to form a contracted throat whereby the air and gas are intermingled and their velocity is increased.
6. In a furnace, a melting chamber, a preliminary combustion chamber communicating with one end thereof, a vertical flue at the outer end of the second chamber to supply air thereto, a vertical flue between the two chambers to supply gas to the second chamber, and an open-top channel in the second chamber into which channel the gas is delivered directly from the gas-flue, the said channel leading to the melting chamber.
7. An open hearth furnace comprising a central melting chamber having a relatively restricted port at each end, a mixing chamber at each end of the melting chamber and communicating therewith through one of said restricted ports, means for discharging air upwardly into the mixing chamber at the end thereof remote from the restricted port, the width of the air stream being substantially coextensive with the width of the mixing chamber, an open topped channel formed on the bottom of the mixing chamber and extending longitudinally from the point of air discharge to the restricted port, and means for discharging gas into said channel.
8. An open hearth furnace comprising a central melting chamber, a mixing chamber at each end of the melting chamber the width of which is, at the furnace end, substantially coextensive with the width of the melting chamber, a relatively restricted port by means of which the mixing chamber is brought into communication with the melting chamber, means for discharging a stream of air upwardly into the mixing chamber at a point remote from the said port, and means for discharging gas upwardly into said mixing chamber at a point intermediate the point of air delivery thereto, and said port.
9. An open hearth furnace comprising a central melting chamber having a relatively restricted port at each end, a mixing chamber at each end of the melting chamber and communicating therewith through one of said restricted ports, each mixing chamber having means for discharging an upwardly moving stream of air thereinto at a point remote from the restricted port, an open topped channel in the bottom of the mixing chamber and extending longitudinally from the point of air discharge to the restricted port, and means for discharging gas into said channel.
10. An open hearth furnace comprising a central melting chamber having a relatively restricted port at each end, a mixing chamber at each end of the melting chamber and communicating therewith through one of said restricted ports, means for discharging air upwardly into the mixing chamber at the end thereof remote from the restricted port, the width of the air stream being substantially coextensive with the width of the mixing chamber, and means for discharging gas into the mixing chamber at a point intermediate the point of air discharge into said chamber and said restricted port.
11. In a furnace, a melting chamber, a preliminary combustion chamber communicating with one end thereof, a vertical flue at the outer end of the second chamber to supply air thereto, a vertical flue between the two chambers to supply gas to the second chamber, and an open-topped channel in the second chamber into which channel the gas is delivered directly from the gas-flue, the said channel leading to the melting chamber and the roof of the second chamber being inclined downwardly toward the first chamber.

HORACE E. SMYTHE.
